MOUNTING SOCKET FOR ELONGATED INCANDESCENT LAMPS

Filed June 29, 1934

UNITED STATES PATENT OFFICE

2,038,270

MOUNTING SOCKET FOR ELONGATED INCANDESCENT LAMPS

Joseph A. Coy, Norwood, Ohio, assignor to The Wadsworth Electric Manufacturing Company, Covington, Ky., a corporation of Kentucky

Application June 29, 1934, Serial No. 733,064

5 Claims. (Cl. 173—332)

The present invention relates to a mounting and energizing socket means for elongated incandescent filament electric lamps wherein the filament extends between terminal caps at opposite ends of the lamp body and has for an object the provision of means whereby such lamps may be simultaneously removably supported and energized.

Another object is to provide a compact double socket for use in mounting and electrically connecting a multiplicity of such elongated lamps in end to end relation.

Another object is to provide a simple and inexpensive construction whereby good electrical contact is attained and secure, quickly removable mounting of the lamps is attained.

These and other objects are attained by the means described herein and disclosed in the accompanying drawing, in which:

Figure 1 is a bottom plan view of an elongated lighting unit having three elongated incandescent illuminating lamps therein, part being broken away.

Figure 2 is a view taken on line 2—2 of Figure 1.

Figure 3 is a view taken on line 3—3 of Figure 1.

Figure 4 is a view taken on line 4—4 of Figure 1.

Figure 5 is a side elevational view of a double socket member of the invention.

Figure 6 is a view taken on line 6—6 of Figure 5.

Figure 7 is a wiring diagram.

Amongst recent developments in elongated tubular incandescent filament lamps is an incandescent lamp of the substantially straight line filament and cylindrical enclosing body that has been prepared for various uses such as decorative illumination, illuminated reflector units, and the like, said novel lamp differing essentially from the heretofore used incandescent filament lamps in that the connector terminals for the filament are very thin and are disposed one at each of the opposite ends of the lamp. The specific details of such lamps form no part of the present invention, it being the primary object of this invention to provide means whereby these lamps may be connected singly, and in numerical series, with a minimum of intervening mounting and electrical connecting means.

The elongated lamps 10 comprise a glass tube 11 sealed at its opposite ends by metallic conductor caps 12 and 13, said caps being identical or dissimilar, but under preferred construction affording but slight projection beyond the ends

of the transparent body 11. Insofar as is known, no convenient means has been provided for electrically connecting opposite sides of supply lines to the opposite ends of the lamp and at the same time providing a secure mounting for said ends.

The device of the invention is herein illustrated as conveniently applied to a reflector casing, but it will be readily understood that the invention, modified only as to the exterior shape and mounting adaptability of the support, may be applied to various types of installation.

In Figure 1 the ordinary lighting trough casing 14 has an open bottom with integral lugs 15 and lugs 16 slightly overhanging the open bottom. A reflector 17 of suitable design is removably secured in the casing by screws 18 passing through a reflector and into arms 19 disposed interiorly of the casing and providing the spacing 20 for the electric conductors 21 from which the lamps are energized. At one end, the casing 14 has a switch 22 of suitable design, mounted interiorly thereof and from which switch one conductor 23 is connected to a fixed mounting and the connector member of the invention shown in cross section in Figure 4. This comprises an insulating member which consists of a base 24 resting upon one pair of lugs 16 and a wall 25 extending at right angles thereto, the wall 25 being of a shape approximating the cross section of the open interior of the trough so as to be easily received therein and slidably positioned beneath the lugs 16. Wall 25 has a circular recess 26 therein of a diameter to somewhat snugly receive the terminal cap 13 of a tubular incandescent lamp. A disc shaped connector terminal 27 is rigidly secured within the depression 26, the disc 27 being suitably dished so that the head 28 of connector screw 29 may seat in countersunk relation therein. The usual nut and washer arrangement 30 serves to electrically connect the bare end of the conductor 23 to the terminal disc 27.

At the opposite end of the casing 14 and slidably received beneath the lugs 16 is a spring urged connector terminal which comprises a body 31 that seats directly on lug 16, and a wall 32, corresponding generally to the wall 25 of Figure 4, but of slightly greater thickness, and having a circular recess or depression therein.

A stud 34 is reciprocable in that portion of the wall 32 which forms a bottom for recess 33 and a connector disc 35 shaped similarly to disc 27 is secured at one end of the stud. Spring 36 is interposed between the bottom wall of recess 33 and the back of the disc and yieldably

urges the disc outwardly of the depression. At the opposite end of stud 34 is a suitable terminal connector nut for attaching the bare end of electric supply conductor 39.

5 When a single elongated tubular lamp 10 is used, the members 24 and 31 are mounted in spaced relation at a distance slightly less than the distance between end caps 12 and 13 of the lamp. With the contacts electrically connected 10 to opposite sides of the light the tube may be mounted and electrically connected between them by merely placing one end of the tube against the yieldably mounted socket terminal and pressing inwardly thereon until the opposite end of 15 the tube is brought into alignment with the disc 37. Upon releasing the tube the spring pressure of the yieldable member firmly mounts the lamp in position. It will be understood that any suitable means may be utilized for mounting 20 the fixed and yieldable mounting sockets and that the shape of the insulating portions thereof may be varied to accommodate specified environments.

When a plurality of the tubular lamps are 25 to be arranged in substantially end to end alignment, the devices detailed in Figures 5 and 6, and shown in operative relation in Figure 1, afford a very compact and efficient mounting and connecting means. The insulating member 30 40 of suitable shape, for example, as shown in Figure 5, has a circular opening 41 extending entirely therethrough and of a diameter to freely receive the diameter of the end caps 12 and 13 of the tubular members. The insulating member 35 40 has a rectangular passage 42 extending radially of the bore 41 and communicating therewith. A double yieldable connector member comprising a pair of contact plates 43 yieldable relative to one another and preferably 40 formed integrally with a U-shaped stem 44 that seats in the passage 42, is secured in position by inserting a threadedly perforate arm 45 of a connector terminal 46 beneath the projecting end of the U-shaped stem and securing the two 45 together with a screw as at 47. The slightly rounded edges 48 of the plates 43 abut the inside periphery of bore 41 so that the plates are yieldable relative to one another but are securely attached to the insulating member 40. The insulating member 40 is counter-bored as 50 at 49 to permit conductor connector screw 50 to be brought down tightly upon a supply conductor whereby both plates 43 are electrically connected with a single wire.

55 Referring to the disclosure in Figure 7, yieldable contact plate 35 is shown in electrical contact with end cap 12 of a tubular incandescent lamp, the filament 51 of which is connected at opposite ends to said caps. The intermediate 60 incandescent lamp 10 is shown mounted with its terminal caps 12 and 13 seated against the yieldably mounted connector plates 43. The non-yielding socket connector 27 is shown at the extreme right. The switch controlled wires 53 and 54 are connected to alternate sockets so that the lamps 10 are wired in parallel but are disposed in linear series. Wire 53 is connected to yieldable terminal plate 35 and to the next 65 non-adjacent pair of yieldable plates 43. The wire 54 is connected to the non-yielding contact plate 27 and its non-adjacent pair of yieldable contact plates 43. The embodiment illustrated shows all forms of the yieldable contact socket and mounting member, but it will be understood 70 that various arrangements of the mounting sock-

ets may be made. For example, two devices such as illustrated in Figure 3 may be employed for a single lamp, or for a plurality of lamps, the devices such as shown in Figures 5 and 6 may be used exclusively, as well as in connection 5 with either or both of the devices shown in Figures 3 and 4.

Under the various modifications of structure embodied within the scope and spirit of this invention, it will be found that the devices are 10 readily made in simple and inexpensive form, and that the mounting and removal of the lamps and also the wiring of the terminal sockets, are 15 speedier and simpler operations than the corresponding operations with the present day screw sockets and the double wired connections there-

to.

What is claimed is:

1. A double socket for lamps of the class described comprising a suitably mounted slab-like 20 insulating support having a bore adapted to receive in its opposite open ends the adjacent ends of two lamps, a conductor terminal comprising an arm lying in abutment with the edge of said support, and yieldable electric contact means intermediate the ends of the bores for exerting 25 yieldable endwise pressure on said lamps, said contact means comprising a looped stem portion embracing said terminal arm and secured there-

to.

2. A double socket for lamps of the class described comprising an insulating member having a bore therethrough, a U-shaped member having its free ends extending transversely into the bore and abutting the wall of the bore to provide yield- 35 ing contacts and a terminal member connected to the U-shaped member and serving to preclude movement of the U-shaped member in a direction transversely of the bore.

3. A double socket for lamps of the kind de- 40 scribed comprising a relatively thin slab of insu- 45 lating material having a bore therethrough in the direction of its thickness and an angular bore extending edgewise therethrough and communicating with the first mentioned bore, a U-shaped metallic member having enlarged free ends and a restricted stem portion, said stem portion adapt- 50 ed to be inserted through the angular bore from within the first mentioned bore and to extend therebeyond, a terminal member comprising an 55 arm adapted to lie in abutment with the edge of the insulating material and to extend through the protruding U-shaped portion of the stem and means fastening the stem and arm together, the relatively enlarged ends of the U-shaped member 60 within the first mentioned bore adapted for edgewise contact on the wall of said first-men- 65 tioned bore and precluding further movement of the stem outwardly through the bore, said 70 arm precluding withdrawal of the stem inwardly 75 through the bore.

4. The combination with a pair of elongated incandescent filament lamps having thin trans- 75 verse end terminals whereby the lamps, when energized, are luminous completely from end to end, of a socket for mounting and energizing adjacent ends of a pair of said lamps comprising a thin body of insulating material having a bore therethrough substantially receiving the thin end terminals of adjacent lamps in opposite ends thereof, said insulated body having a second bore extending from an edge thereof and communicating with the first mentioned bore, a U-shaped integral double contact member having 80 its end developed into relatively wide and yield- 85 90 95 98

ably spaced plates and further having its connected end forming a relative U-shaped stem insertable through the edgewise bore from within the lamp receiving bore whereby the plate portions may abut edgewise upon the wall of the last mentioned bore, said narrow U-shaped stem forming a protruding loop at the edge of the body and a conductor terminal member insertable in sliding abutment with said edge of said insulating body and through said protruding loop whereby the terminal and the U shaped double contact member mutually secure themselves upon the insulating body and permitting the plate portions under the pressure of opposed inserted lamps, to move into substantial abutment.

5. In a socket, the combination of a relatively thin insulating body having a lamp receiving bore therethrough, a contact strip extending transversely into the bore intermediate the ends thereof, a restricted stem on the contact strip 5 extending through the body from said bore to the edge of the body, a connector terminal abutting the edge of the body and interengaging with the edge of the stem and means to rigidly secure the stem and terminal together whereby said parts mutually retain one another in position relative to the insulating body. 10
